UNITED STATES PATENT OFFICE.

RICHARD H. RICE, OF WEST LYNN, MASSACHUSETTS, ASSIGNOR TO GENERAL ELECTRIC COMPANY, A CORPORATION OF NEW YORK.

MEANS FOR CHANGING THE OUTPUT OF CENTRIFUGAL COMPRESSORS.

1,118,443.

Specification of Letters Patent. Patented Nov. 24, 1914.

Application filed October 3, 1911. Serial No. 652,564.

To all whom it may concern:

Be it known that I, RICHARD H. RICE, a citizen of the United States, residing at West Lynn, county of Essex, State of Massachusetts, have invented certain new and useful Improvements in Means for Changing the Output of Centrifugal Compressors, of which the following is a specification.

Centrifugal air compressors when employed in the usual and normal manner in blast furnace work, furnish a constant or substantially constant number of cubic feet of free air per minute. There are times, however, when the amount of air required by the consumption devices is only a fraction of the normal amount delivered by the compressor. The problem presented is, therefore, to provide a governing mechanism for a compressor and its driving motor which is capable of being so adjusted or modified in its action, that the compressor instead of delivering its normal output, may deliver any fraction thereof at a predetermined pressure. The adjusting or modifying means must operate in a simple manner, require little time to adjust and not necessitate shutting down the apparatus or taking it apart in making said adjustment.

For a consideration of what I believe to be novel and my invention, attention is directed to the accompanying description and claims appended thereto.

In the drawing is shown a centrifugal compressor and a turbine for driving it, the compressor and turbine being shown side by side to simplify the illustration.

1 indicates a driving motor. This may be a steam turbine of the Curtis or other type. It is provided with a regulator comprising 40 a valve chest 2, containing one or more valves that are actuated by the cam shaft 3 in the well-known manner. On the shaft is an arm 4 that is actuated by a float located in the intake of the compressor.

45 5 indicates a part of the casing of a centrifugal compressor and 6 the intake therefor. Located within the intake pipe is a float 7

that rises and falls as the rate of flow of air through the compressor varies. The float operates in the manner set forth in my Patent 919,953, dated April 27, 1909, and this invention may be regarded as an improvement over that claimed in said patent.

The structure of the patent is, however, arranged to deliver fluid at but one predetermined constant rate of flow, whereas the structure of the present invention is arranged to deliver air at many different rates of flow, each of which is constant when once established. The float 7 is mounted on a rod 8 that extends upwardly through the top of the casing and is connected to the tilting scale beam 9. This beam is pivoted at 10 on the bracket 11 and is provided with teeth or notches to hold a weight in position, as will appear later. The beam also has a suitable scale to guide the attendant in making adjustments. In the present instance as an illustration, a quadratic scale is provided and laid off to indicate zero-flow, also a flow of twenty thousand, thirty thousand and forty thousand cubic feet of free air per minute. Connected to the beam is an arm 12 that is united by the rod 13 with the regulator of the motor, as for example with the arm 4 on the cam shaft of the steam turbine. To the left hand end of the beam is connected a rod 14 and piston 15, the latter being located in the cylinder 16 and cooperating therewith to form a dash-pot. An adjustable by-pass 17 serves to regulate the effective action of the dash-pot.

Mounted on the right hand end of the beam 9, and adjustable thereon, is a weight 18 that counterbalances to a certain predetermined extent, the weight of the float 7, dash-pot parts, etc. The remainder of the weight is supported by the fluid flowing upward through the intake. This weight 18 is usually adjusted once for all when the parts are initially assembled. It corresponds in function to the weights 23 of my Patent 919,953, aforesaid, but it has the advantage of being more readily adjustable. With in-

2
dividual weights supported as in said patent, considerable work may be involved in getting the exact balance desired.

5 The means for adjusting the mechanism to cause different but constant rates of flow of air at predetermined pressure to be delivered will now be considered.

10 Mounted on the notched scale beam 9 is an adjustable sliding weight 19 having a suitable handle 20 for moving it. When the weight 19 is in the zero-flow position and the weight 18 is in the proper position, the parts are balanced. Air flowing upward through the intake exerts a force on the lever 9 through the rod 8, tending to move it upward. As the weight 19 is moved along the scale beam from the position shown, toward the left, the opposition to the upward movement of the float is changed and the 15 rate of flow of air through the compressor is therefor increased. This is due to the fact that the changed position of the weight causes a depression of the left hand end of the beam and with it the float 7 to a new 20 and lower position. This action moves the regulator of the motor in a direction to cause the speed of the motor to increase. Naturally as the speed of the motor increases, the impeller of the compressor will 25 rotate at a higher speed and discharge a greater amount of air per unit of time. The amount of air flowing through the intake will, for any given condition, ultimately reach such a value as to balance the effective action of the weight 19 on the beam and when this occurs the speed of the driving motor will become substantially constant as will also the output of the compressor. This output is greater for each 30 successive position of the weight 19 toward the left from the initial position. The parts are so proportioned and related, that a movement to the left of the weight 19 steadily increases the rate of flow per unit of 35 time until the maximum is reached when the pointer 21 will enter or coincide with the notch in the scale beams indicating 40,000 cubic feet of free air. To decrease the rate of flow, assuming the weight 19 to be set for 40 maximum delivery, said weight is moved to the right which permits the float and co-operating beam to close one or more valves in the turbine and decrease its speed.

45 The weight of the dashpot rod 14 and piston 15, the float 7 and its rod 8, etc., make the zero position of the weight 19 fall considerably to the right of its pivot 10, as shown, and for ordinary ranges of velocity this allows the beam 9 to be pivoted about 50 its middle instead of at or near its left-hand end. This makes the apparatus more compact and convenient.

55 The compressor illustrated is intended for a maximum output of 40,000 cubic feet of 55 free air per minute, but my invention is not

limited thereto as it is capable of wide application.

70 The scale beam occupies a substantially horizontal position at all times, and since the position of the weight 19 thereon can readily be seen, it serves as a visual indicator to indicate the rate of flow of air through the apparatus. This is of special advantage when it is desired to know easily and quickly 75 how much the apparatus is delivering. It will be evident of course, from the construction illustrated that the slight inclination of the beam will be different for different outputs of the compressor and different discharge pressures.

80 In accordance with the provisions of the patent statutes, I have described the principle of my invention, together with the apparatus which I now consider to represent the best embodiment thereof; but I desire 85 to have it understood that the apparatus shown is only illustrative and that the invention can be carried out by other means.

85 What I claim as new and desire to secure by Letters Patent of the United States, is,

90 1. The combination of a rotary compressor, a driving motor and regulating means therefor, a float located in a passage through which the fluid acted on by the compressor passes so as to float on the flowing fluid and respond to variations in its rate of flow, a rod connected with said float and extending through the wall of said passage, a beam pivotally mounted on said wall to which 95 said rod is connected intermediate its ends at one side of the pivot, a weight at one end of said beam for the purpose of initially balancing it under conditions of zero flow, an additional weight adjustable along said beam to enable the device to be set so as to 100 maintain any desired rate of flow, said beam having on it a scale for indicating the rates of flow corresponding to various positions of said latter weight, a dashpot device comprising a stationary part secured to said 105 wall and a movable part connected to said beam at the other end, and an operative connection joining said motor regulating means 110 to said beam at a point intermediate between its ends.

115 2. The combination of a rotary compressor, a driving motor and regulating means therefor, a float located in a passage through which the fluid acted on by the 120 compressor passes so as to float on the flowing fluid and respond to variations in its rate of flow, a rod connected with said float and extending through the wall of said passage, a pivotally mounted beam to which 125 said rod is connected at one side of the pivot, a weight on said beam for the purpose of initially balancing it under conditions of zero flow, an additional weight adjustable along said beam from one side of the pivot to the other to enable the device to be set so 130

as to maintain any desired rate of flow, said beam having on it a scale for indicating the rates of flow corresponding to various positions of said latter weight, and an operative connection between said beam and said motor regulating means.

5 In witness whereof, I have hereunto set

my hand this Thirtieth day of September, 1911.

RICHARD H. RICE.
